UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed October 29, 1917, Serial No. 199,053. Renewed October 10, 1929.

My invention relates to mining machines.

It has heretofore been proposed to drive entries by means of what is known as the arc-wall system. In this system, truck mounted machines are utilized adapted to travel upon rails to the wall of the entry and having a forwardly extending horizontal cutter bar disposed in a plane above the level of the rails and movable about an axis located in the center line of the truck. In the operation of this system, the bar is angled relative to the track and is, first, advanced into the coal by a rectilinear movement; second, swung across in the same transverse plane; and, third, retracted when disposed at the opposite side of the machine at an angle relative to the track corresponding to the first angle. However, with such a machine it has been impossible to make the cutting mechanism operate on the bottom of the entry, due to the interference of the track, and the result has been that in those operations undercut coal to the depth of six or eight inches, i. e. the height of the track, has been left in a substantially solid mass beneath the kerf, even after the coal has been shot, thereby contributing so largely to the difficulties in the way of cost and delay incident to the use of this system as to be prohibitive under ordinary conditions, and especially so when labor is scarce and available only at a price.

My invention has for its object to drive a mine entry in an improved manner whereby the bottom of the kerf may form a continuation of the plane of the entry bottom.

A further object of my invention is to provide improved mechanism whereby the operation of removing the coal from an entry may be facilitated and the delay and cost of entry driving decreased, through the use of improved means whereby the machine may cut its kerf not only in the plane of the entry bottom, but across the end of the rails. A more specific object of my invention is to provide an improved entry driving mechanism whereby it is made possible to undercut the material of the entry on a level with the entry bottom in such a manner that all the coal may be shot and removed in one operation, all necessity for a separate operation of

removing any layer of coal above the bottom being eliminated. I attain these objects by an apparatus operating in accordance with an improved method whereby the cutter bar is enabled to operate on the same level as the bottom of the entry and in a path across the end of the track and in advance of the machine.

In the accompanying drawings, I have, for purposes of illustrating the principle of my invention, shown one embodiment which the same may assume in practice, illustrating the same as applied to a machine of the well known arc-wall type.

In these drawings,—

Fig. 1 is a plan view of my improved machine, the parts being shown in one of the transport positions.

Fig. 2 is a side elevation of the construction shown in Fig. 1.

Fig. 3 is a simplified diagrammatic view showing the machine in position to make its sumping cut.

Fig. 4 is a similar view showing the machine after completing its sumping cut.

Fig. 5 is a similar view showing the machine after the completion of its transverse cut.

Fig. 6 is a similar view showing the machine adjusted into position to begin its withdrawal cut.

Fig. 7 is a similar view showing the machine after the completion of its withdrawal cut, another transport position being shown in dotted lines.

Fig. 8 is a similar view showing the machine in use as a long-wall machine.

In this illustrative disclosure, it will be noted that the machine includes a truck frame 1 rigidly supported upon suitable wheels 2 which are adapted to run upon the track 3 and be driven from suitable propulsion means. Herein, the power for driving these wheels is derived from a suitable motor 4 mounted on the truck and operatively connected through gearing 5 to truck driving mechanism 6 including a transverse truck shaft at the rear of the truck, the motor being controlled through a suitable controller 7 and the rotation of the shaft being con-

trolled through a suitable clutch and brake 8 of the usual reversible type whereby the movement of the truck may be controlled and reversed in a well known manner. Carried upon the truck it will also be observed that I have shown a reel 9 adapted to wind or unwind a cable 10 connected to the motor and thus supply current to the latter during transport. Thus, it will be evident that means are provided whereby the truck 1 may be reciprocated at will back and forth relative to the track 3.

Carried upon the truck 1 is a rotatable member 11, which may assume various forms but is herein shown as substantially circular in form and mounted upon suitable supports 12 and 13, non-rotatably mounted upon the front end of the truck 1 and connected by adjusting the screws 14 in such a manner that the height of the member 11 may be adjusted as desired. As shown, the element 12 forms a table-like support on which the member 11 is journaled, and this member 12 is provided with depending portions adapted to cooperate with a plurality of screws 14 rotatably mounted in the support 13 and disposed at a plurality of points beneath the member 11 in such a manner as to furnish a stable support therefor, three of these points of support being shown herein. As illustrated, the screws 14 are also connected with power mechanism in such a manner that the height of the member 12, and therefore of the member 11 carried thereon, may be varied as desired, the means for adjusting the same being shown herein as including a plurality of sprockets 15 carried on the lower end of the screws and connected through a suitable chain 16 to a sprocket 17 carried on a vertical shaft 18 at the rear of the truck 1 and in turn connected through beveled gearing 19 to a shaft 20 connectable at will with the shaft 6 through suitable clutch mechanism 21.

Cooperating with the rotatable member 11 and adjustable therewith, is the cutting mechanism, shown herein to include a forwardly extending, horizontally disposed cutter bar 22 carrying the usual revolute cutter chain 23. As shown, the inner end of this chain 23 is connected to a suitable sprocket 24 journaled in suitable bearings on a forwardly and downwardly extending support 25 disposed in front of the member 11 and rigidly connected thereto, the support 25 being shown herein as cast integral with the member 11. As shown, the sprocket 24 is connected to a suitable upstanding shaft 26 journaled in the support 25, which in turn carries a sprocket 27 on its upper end connected through a rearwardly extending chain 28 to another sprocket 29 disposed over the axis of the rotatable member 11 and connected through suitable transmission mechanism to a suitable source of power.

As shown, the power for rotating the chain 23 is supplied from a suitably controllable motor 30 carried on the under side of the rotatable member 11 and connected through suitable transmission mechanism 31, 32, 33, and 34 with the sprocket 29 whenever a clutch 35 is adjusted into operative position to connect the idler member 32 to its shaft 33. 70

As shown, means are provided herein whereby the angular position of the rotatable member 11 may be varied as desired, preferably by power means. These means, as shown, include a gear 36 meshing with the idler gear 32 and carried upon a transverse shaft 37 which is in turn connected through beveled gearing 38 with a rotating drum 39 carried on the top of the member 11 and adapted to wind up a cable or suitable flexible member 40 passing around suitable sheaves 41 disposed around the periphery of the member 11 and having its free end connected, as shown at 42, to the stationary truck member 1. Thus, obviously, power may be supplied from the motor 30 to wind and unwind the drum and thereby vary the angular position of the member 11. It will also be noted that through a suitable adjustable friction clutch 43 of any well known form, herein of the hand-wheel type and carried within the drum, the connection of this drum to the power shaft 37 may be varied as desired, and that through the provision of a locking member 44 carried on the support 12 and adapted to be received in any one of a plurality of notches 45 formed in the edge of the member 11, the latter may be locked in any desired angular position. 90

Thus, it will be observed that the machine may be moved bodily back and forth when desired, along the rails 3 through the operation of the motor 4 and the connection of the latter to the truck wheels; that the cutter chain 23 may be operated when desired from the motor 30 through the connections between these elements including the chain 28; that the height of the rotatable member 11 and the cutter bar may be varied as desired through the operation of the connection between these elements including the chain and sprocket connection 17, 16, 15; and that the angle of the member 11 may be adjusted when desired through the power connections including the flexible connection 40 and the controlling members therefor. It will also be evident that through the provision of the several clutch mechanism the various mechanisms may be operated in any sequence desired. 100

In the form of my improved construction shown herein, it will be noted that the cutter bar 22 may be so adjusted relative to the rotatable member 11 as to enable the bar to be lowered into position to cut at one side of the rail 3 and on the same level as, i. e. flat upon, the bottom of the entry. It will also 110

be observed that means are provided whereby after the bar is so disposed the same may be swung in the same plane across the front end of the rails 3 and thereafter caused to be moved rectilinearly in the same plane in such a manner as to cause the entire continuation of the entry to be in the form of an undercut on the same level as the floor of the entry. More specifically, it will be observed that the bar 22 is revoluble relative to its support 25, and that through the provision of suitable adjusting means the same is adapted to be adjusted into various operative positions angularly with respect to this support. These means may obviously assume various forms, but as shown the same comprise a laterally extending arm 46 operatively connected to the bar 22 through a suitable sleeve 47 surrounding the shaft 26, and a cooperating pin 48 adapted to be received in a plurality of suitable apertures 49, 50, 51, 52, and 53, in a forwardly and, herein, laterally extending plate 54 connected to the front end of the rotatable member 11. Thus, it will be noted that not only may the angular position of the bar be adjusted by rotation of the rotatable member 11 when the bar is locked in any given position thereon, but that, through this adjustment and the lowering mechanism 15, 16, the position of the bar 22 relative to this member 11 and the truck may be so adjusted as to enable the bar to be swung laterally in such a manner that the chain 23 may cut on the bottom at either side of the rails and, when the machine is located at the end of the rails, pass transversely across beyond the front of the latter. It will also be observed that the location of the kerf is controllable by the adjusting mechanism 15, 16 so that the kerf may be thus inserted as a continuation of the bottom or at any desired height above the bottom. Attention is also directed to the fact that the mechanism may be operated in the usual manner and without the use of this adjustment whenever it is desired to cut out a kerf above the bottom level.

The operation of my improved mechanism will be more clearly understood from a consideration of Figs. 3 to 7, wherein the machine is illustrated diagrammatically in the various positions which it will assume during the operation of under-cutting an entry on the level of the entry bottom. During the transport of the machine about the mine, the parts may, if desired, obviously occupy the position shown in Fig. 1. When, however, the machine has been moved into the entry until the end of the bar is closely adjacent the face, the parts are then adjusted into the position shown in Fig. 3. In this position, it will be noted that the truck is not run quite to the end of the rails 3, and that the bar is swung to the right and flexed relative to the member 11 which also has been turned to

the right. Preferably, this adjustment is made before the cutter bar is started in operation and after the pin 48 has been removed, by means of the power driven flexible connection 40 which acts to swing the member 11 and the bar to the right until the end of the latter is brought against the right hand wall or rib of the entry in such a manner as to flex the pivotal connection between the bar 22 and the rotatable element 11 until the parts assume the position shown in Fig. 3. In this position it will be observed that the pin 48 may be readily inserted in registering openings. It will also be noted that the bar is then so disposed at the outside of the right hand rail 3 that it may be lowered upon the bottom by a suitable operation of the adjusting screws 14, and that the bar is then rigidly connected to the truck in such a manner that when the cutter chain is started in operation and the entire truck 1 reciprocated forward from the position shown in Fig. 3 to the position shown in Fig. 4, the bar may be readily dumped in under the coal on the level of the entry bottom. In this position, i. e. that shown in Fig. 4, wherein the truck has been moved forward to the extreme end of the rails, the truck is maintained stationary by any suitable means, as for instance through the reaction of the gear 5 or the use of other suitable means to hold it during the making of the transverse cut. With the parts in this position, this cut may then, obviously, be made across from the position shown in Fig. 4 to the position shown in Fig. 5 by simply operating the flexible connection 40 in such a manner as to cause the rotatable member 11 to be rotated to the left relative to its support, the bar cutting substantially throughout its length during the greater part of its bodily transversely swinging movement. When the parts reach the end of this transverse cut, i. e. the position shown in Fig. 5, however, it will be noted that the inner end of the cutter chain would strike the left hand rail if the cutting mechanism were then bodily withdrawn, and that it is accordingly necessary to swing the same to the left and outside the left hand rail 3. This is again readily accomplished by removing the pin 48 and operating the flexible connection 40 in such a manner as to swing the pivotal connection of the bar slightly to the left and cause the parts to assume the position shown in Fig. 6, whereupon the pin 48 may be readily dropped into the registering holes. During this operation, obviously, the cutter chain 23 may be operated in such a manner as to reduce the amount of uncut material to the extent shown in Fig. 6, so that cutting may continue during this movement of the cutter bar to a point outside the limits of the left hand rail. Obviously, after the parts have reached the position shown in Fig. 6 the same may be readily withdrawn from

the cut to complete the latter by a single rearward reciprocation of the truck 1 on the track, the parts then assuming the full-line position shown in Fig. 7. When in this position the cutter bar may obviously be raised from the bottom through a simple operation of the screw 14, and the same may be swung into the position shown in dotted lines by a simple operation of the flexible connection 40 in order to prepare the mechanism for transport to the next entry to be cut, the bar then being so disposed that it does not interfere with the ready transport of the machine about the mine. Also, it will be observed that with the bar in this position, when it is again desired to adjust the same into the position shown in Fig. 3 in order to make the first cut in the next entry, it is only necessary to remove the pin 48 and rotate the table 11 to the right in order to flex the pivotal connection by power means and bring the parts into the position shown in Fig. 3, wherein after the return of the pin and the lowering and starting of the cutter bar the next forward cut may be made.

In the use of my improvement, it will be observed that it is possible to extend an entry by cutting continuously upon the same level and without leaving any uncut portions to be removed before the track can be again advanced, thus greatly reducing the expense incident to the operation of entry driving with known machines, at the same time that the speed of entry driving is materially increased. By the use of my improved construction it is also possible to drive an entry having straight ribs, the forward or sumping cut producing a straight right hand rib, while the rearward or withdrawal cut produces a straight left hand rib. It will also be observed that by the use of my improved mechanism all various adjustments of the bar may be made by power means, the only labor required of the operator being the simple operation of removing the pin 48 and re-inserting the same after the power means has so moved the elements that the pin-receiving holes are in registry. Attention is also directed to the fact that whenever desired, my improved machine may be readily adapted to long-wall work, as shown in Fig. 8, by simply swinging the bar to a position at right angles relative to the truck, preferably while the cutter bar is operating, and then maintaining the bar in this position as the truck is moved along the wall or face. Obviously, by such an arrangement it will be possible to produce a bottom cut extending along the length of any face so that the machine may be used in either long-wall or room cutting. It will also be evident that by the use of my improved construction, the level or angle of the kerf may be varied within any desired limits and that, when desired, the machine may be operated as an ordinary arc-wall machine, the same having all the

advantages thereof at the same time that it is enabled to produce numerous new and improved results not obtainable by such a machine. These and other advantages of my improvement will, however, be clearly apparent to those skilled in the art.

While I have in this application specifically described one embodiment which my invention may assume in practice, it will be understood that the same is used only as an illustration of the principle of the invention and that the invention itself may assume various other forms without departing from its spirit or from the scope of the appended claims.

What I claim as new and desire to secure by Letters Patent is:

1. In a mining apparatus, a wheeled truck adapted to run along a mine trackway, a support mounted on said truck for adjustment bodily vertically rectilinearly relative thereto and for rotative movement about a vertical axis, kerf cutting mechanism on said support including a pivoted cutter bar swingable about a parallel vertical axis and provided with cutting elements moving in an orbit within whose limits the pivot of said bar is disposed, and means, including motor operated devices for adjusting and rotating said support relative to said truck, for disposing said bar in transverse planes beneath the level of the top of the trackway with its pivot at one side of the trackway, and for positioning said bar substantially above the top of the trackway.

2. In a mining apparatus, a wheeled truck adapted to run along a mine trackway, a support mounted on said truck for adjustment bodily vertically rectilinearly relative thereto and for rotative movement about a vertical axis, kerf cutting mechanism on said support adapted to cut in spaced horizontal planes and including a pivoted cutter bar swingable about a parallel vertical axis and provided with cutting elements moving in a substantially horizontal orbit, and means, including motor operated devices for adjusting and rotating said support relative to said truck, for disposing said bar in transverse planes beneath the level of the top of the trackway and wholly at either side of the trackway.

3. In a mining apparatus, a wheeled support adapted to run along a mine trackway, a turntable mounted on said support for rotation about a vertical axis, kerf cutting mechanism mounted on said turntable including an elongated plane kerf cutter pivotally mounted on said turntable to swing about an axis parallel to the turntable axis but spaced therefrom to enable bringing the bar wholly outside the trackway, means, including motor operated devices for adjusting said turntable vertically relative to the support wheels, for adjusting said kerf cut-

ting mechanism to position said kerf cutter in transverse planes beneath the top of the trackway with its pivot at one side of the trackway to make a horizontal cut at the level 5 of the mine bottom, and means including motor operated devices for sumping said bar when so disposed bodily rectilinearly into the coal, moving the same bodily to make a swinging cut across the end of the trackway, 10 and moving the same bodily reversely of the trackway, to make a parallel ribbed kerf on the level of the bottom in advance of the trackway.

4. In a mining machine, the combination 15 with a self propelling wheel supported truck having mechanism for driving the wheels thereof to effect truck propulsion, of a turn-table rotatably mounted upon said truck and vertically adjustable relative thereto, an over-hanging bracket carried by said turntable, a horizontally projecting elongated kerf cutter mounted upon said bracket and rotatable thereon in horizontal planes, means to lock 20 said kerf cutter in either of several positions of angular adjustment relative to said bracket, and means mounted upon said turntable to actuate the kerf cutter and to rotate the turntable as and for the purpose set forth.

5. In a mining machine, the combination 25 with a self-propelling wheel supported truck having mechanism for driving the wheels thereof to effect truck propulsion, of a turn-table rotatably mounted upon said truck and vertically adjustable relative thereto, an over-hanging downwardly projecting bracket carried by said turntable, a horizontally projecting elongated kerf-cutter mounted upon the lower end of said bracket and rotatable thereon in horizontal planes, means to lock 30 said kerf-cutter in either of several positions of angular adjustment relative to said turn-table, and means mounted upon said turn-table to actuate the kerf-cutter and to rotate the turntable as and for the purpose set forth.

45 6. In a mining machine, the combination with a self-propelling wheel supported truck having mechanism for driving the wheels thereof to effect truck propulsion, of a turn-table rotatably mounted upon said truck and vertically adjustable relative thereto, an overhanging downwardly projecting bracket carried by said turntable, a horizontally projecting elongated kerf-cutter mounted upon the lower end of said bracket and rotatable 50 thereon in horizontal planes, means to lock said kerf-cutter in either of several positions of angular adjustment, means mounted upon said turntable to actuate the kerf-cutter and to rotate the turntable, and means to lock the turntable.

7. In a mining machine, the combination 55 with a self-propelling wheel supported truck having mechanism for driving the wheels thereof to effect truck propulsion, of a supporting member rotatably mounted upon said

truck and turntable in horizontal planes and bodily vertically adjustable relative to the truck wheels, a radially and downwardly extending bracket carried by said supporting member, a horizontally projecting elongated 70 kerf cutter mounted upon the lower and outer end of said bracket and pivotable thereon and relative thereto in horizontal planes, means to lock said kerf cutter in either of several positions of angular adjustment relative to said bracket, and motor-operated means to actuate the kerf cutter and to rotate the rotatably mounted supporting member and to feed the truck during cutting.

8. In a mining machine, the combination 75 of a wheeled track guided truck providing a base arranged in fixed relation to the axes of the wheels, a vertically pivoted frame member mounted above said base, supporting means for the latter permitting bodily vertical adjustment thereof relative to said base, an arm projecting from said vertically pivoted frame member and provided with a depending bracket, and cutting mechanism including a pivoted cutter bar pivoting on said depending bracket on said arm, driving means for said cutter bar including a vertical shaft disposed in said bracket, a motor on said frame, and driving connections between said shaft and motor, said parts being constructed and arranged to permit said bar to be lowered to the bottom upon which a track guiding the truck wheels is positioned, and a motor separate from said first mentioned motor for effecting the raising and lowering 100 of said bar rectilinearly.

9. In a mining machine, the combination 105 of a wheeled track-guided truck providing a base arranged in fixed relation to the axes of the wheels, a vertically pivoted frame member mounted above said base, supporting means for the latter permitting bodily vertical adjustment thereof relative to said base, an arm projecting from said vertically pivoted frame member and supporting a depending bracket, and cutting mechanism including a pivoted cutter bar pivoting on said depending bracket on said arm, driving means for said cutter bar including a vertical shaft disposed in said bracket, a motor on said 110 frame, and driving connections between said shaft and motor, said parts being constructed and arranged to permit said bar to be lowered to the bottom upon which a track guiding the truck wheels is positioned, and a motor separate from said first mentioned motor for effecting such lowering and the raising of the bar, the distance between the axis of said vertical shaft and the axis of said pivoted frame being substantially 115 more than one-half the width of such trackway whereby said bar may lie flat on the bottom outside the trackway.

10. In a mining machine, the combination 120 with a wheeled track guided truck providing

a base, a turntable mounted thereon and including a ring adjustable vertically relative to said base but held against rotary movement with respect thereto, a rotatable turntable 5 element supported and guided by said ring and rotatable on a vertical axis passing through the center of said ring, a cutter bar supported by and pivotally mounted relative to said rotatable turntable element to 10 swing about an axis parallel to but offset from the axis of the turntable, said axis of bar swing falling outside said ring, means for locking said bar in a plurality of predetermined angular positions relative to said turntable and said turntable in a plurality of predetermined angular positions relative to said base, and a motor operative to vertically adjust the ring.

11. In a mining machine, a truck adapted 20 to run upon a track, cutting mechanism thereon including a pivoted cutter bar provided with cutting elements moving in an orbit within which the pivot of the bar is disposed, and means for supporting the bar 25 and permitting the same to be disposed in a transverse plane beneath the top of said track with its pivot at one side of said track including a vertically adjustable bar supporting mechanism including a vertically rectilinearly reciprocable member affording a 30 bearing and a bar supporting member mounted in said bearing for rotation on a vertical axis, and a motor for effecting vertical adjustment of said last mentioned elements and feeding of said machine.

12. In a mining machine, a wheeled truck 35 movable over a trackway, a horizontal turntable mounted thereon, cutting mechanism carried by said turntable and including a 40 cutter bar having circulating cutting elements and pivoted to swing about an axis offset from but parallel to the axis of rotation of said turntable, means for holding said cutter bar in different horizontal angular 45 positions relative to a straight horizontal line intersecting the pivotal axes of the bar and of the turntable, actuating means for said cutter bar operative to effect circulation of said cutting elements including a motor 50 mounted on said turntable and driving connections between the same and said cutting elements, and motor operated means for adjusting said bar vertically rectilinearly between positions wherein the bottom of the 55 horizontal kerf cut thereby will constitute a continuation of the surface upon which the trackway is mounted and wherein the bottommost points of the bar and cutting elements will be above a horizontal plane above 60 the top of the track.

13. In a mining machine, a wheeled truck 65 movable over a trackway, a horizontal turntable mounted thereon, cutting mechanism carried by said turntable and including a 70 cutter bar having circulating cutting ele-

ments and pivoted to swing about an axis offset from but parallel to the axis of rotation of said turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving connections 75 between the same and said bar, and motor operated means for adjusting said bar vertically rectilinearly between positions wherein the bottom of the horizontal kerf cut thereby will constitute a continuation of the surface upon which the track along which the truck runs is mounted, and wherein the bottommost points of the bar and cutting elements will be above a horizontal plane above 80 the top of the track, and motor driven driving means for said truck wheels.

14. In a mining machine, a wheeled truck 85 movable along a trackway, a horizontal turntable mounted thereon, cutting mechanism carried by said turntable and including a 90 cutter bar having circulating cutting elements and pivoted to swing about an axis offset from but parallel to the axis of rotation of said turntable, means for holding said cutter bar in different angular positions relative to a straight horizontal line intersecting the pivotal axis of the bar and of the turntable, actuating means for said cutter bar operative to effect circulation of said cutting elements including a motor mounted on said 95 turntable and driving connections between the same and said bar, motor operated means for adjusting said bar vertically rectilinearly between positions wherein the bottom of the horizontal cut thereby will constitute a 100 continuation of the surface upon which the track along which the truck runs is mounted, and wherein the bottommost points of the bar and cutting elements will be above a plane above the top of the track, motor driven driving mechanism for said truck wheels, and a common motor for effecting 105 driving of the truck wheels and effecting the vertical adjustment of the cutter bar specified.

15. In a mining machine, a wheeled truck 110 movable along a trackway, a horizontal turntable mounted thereon, cutting mechanism carried by said turntable and including a 115 cutter bar having circulating cutting elements and pivoted to swing about an axis offset from but parallel to the axis of rotation of said turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving connections 120

between the same and said bar, and motor operated means for moving said turntable vertically rectilinearly to bring said bar into positions wherein the bottom of the horizontal kerf cut thereby will constitute a continuation of the surface upon which the track along which the truck runs is mounted and wherein the bottommost points of the bar and cutting elements will be above a plane above the top of the the track.

16. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis of rotation of said turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving connections between the same and said bar, a second motor, means operated thereby for adjusting said bar vertically rectilinearly between positions wherein the bottom of the horizontal kerf cut thereby will constitute a continuation of the surface upon which a track along which the truck runs is mounted, and wherein the bottommost points of the bar and cutting elements will be above a plane above the top of the track, and means operated by said first mentioned motor for changing the angle of said bar to a working face.

17. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis of rotation of said turntable, means for holding said cutter bar in different horizontal angular positions relative to a straight horizontal line intersecting the pivotal axes of the bar and of the turntable, actuating means for said cutter bar operative to effect circulation of said cutting elements including a motor mounted on said turntable and driving connections between the same and said bar, a second motor, means operated thereby for adjusting said bar vertically rectilinearly between positions wherein the bottom of the horizontal kerf cut thereby will constitute a continuation of the surface upon which the track along which the truck runs is mounted and wherein the bottommost points of the bar and cutting elements will be above a plane above the top of the track, and said bar being disposable on the bottom wholly outside the track and making a less angle

with the track than the angle between said horizontal straight line and the line of the track.

18. In a mining machine, the combination of a wheeled track guided truck providing a base arranged in fixed relation to the axes of the wheels, a vertically pivoted frame mounted above said base, supporting means for the latter permitting vertical adjustment thereof relative to said base, a cutter chain carrying cutter bar member carried by and pivotally mounted with respect to said frame for swinging movement about an axis parallel to but offset from the axis of said frame, a motor on said frame operatively connected to said cutter chain, and means for holding said bar in different adjusted positions relative to said frame including a plurality of holes in one of said members, a hole in the other and a pin adapted to be inserted in said holes.

19. In a mining machine, a wheeled truck adapted to run upon a track, and cutting means supported by said truck including an elongated plane cutter chain carrying cutter bar, a member rotatable upon an axis perpendicular to the plane of said bar and to which said bar is connectible for swinging at an angular rate the same as that at which said member rotates on its axis, motor operated means for adjusting said member upwardly and downwardly relative to the truck wheels, motor operated means for actuating the cutter chain on said bar in its different positions resulting from adjustment upwardly or downwardly of said member, motor operated means supported by said truck for rotating said member at a cutting speed, and locking means releasable at will for connecting said bar rigidly to said member for swinging thereby or for releasing the bar to permit the same to swing freely relative to said member.

20. In a mining machine, a wheeled truck adapted to run upon a track, and cutting means supported by said truck including an elongated plane cutter chain carrying cutter bar, a member rotatable upon an axis perpendicular to the plane of said bar and to which said bar is connectible for swinging at an angular rate the same as that at which said member rotates on its axis, motor operated means for adjusting said member upwardly and downwardly relative to the truck wheels, motor operated means for actuating the cutter chain on said bar in its different positions resulting from adjustment upwardly or downwardly of said member, motor operated means supported by said truck for rotating said member at a cutting speed, and locking means releasable at will for connecting said bar rigidly to said member for swinging thereby or for releasing the bar to permit the same to swing freely relative to said member including means providing a series of

spaced abutment surfaces arranged along an arc are struck from the pivotal axis of said bar and a locking element insertible in engagement with different ones of said surfaces and bearing a like relation to the cutter bar when the latter is locked in different positions.

21. In a mining apparatus, a wheel supported body adapted to travel along a mine trackway, a frame mounted on said body for horizontal swinging movement relative thereto about a vertical axis, said frame overhanging the front end of said body, kerf cutting mechanism including a horizontal plane kerf cutter pivotally mounted on the outer extremity of said frame to swing horizontally relative thereto about an axis parallel to said frame axis, said kerf cutter being adjustable into different elevated positions while the plane of said kerf cutter always remains horizontal, motor operated devices for adjusting said kerf cutter into the aforesaid elevated positions, said kerf cutter being adjustable into a position to cut a horizontal kerf at the level of the mine floor outside and below the level of the mine trackway, and motor operated devices for swinging said frame about its axis and for driving said cutting mechanism including a motor mounted on and swingable with said frame.
22. In a mining apparatus, a wheel supported body adapted to travel along a mine trackway, a frame mounted on said body for horizontal swinging movement relative thereto about a vertical axis, said frame overhanging the front end of said body, kerf cutting mechanism including a kerf cutter pivotally mounted on the outer extremity of said frame to swing horizontally relative thereto about an axis parallel to said frame axis, said frame being adjustable in a vertical direction to vary the elevation of said kerf cutter, motor operated devices for adjusting said frame in aforesaid vertical direction to position said kerf cutter to cut a horizontal kerf at the level of the mine floor outside and below the level of the mine trackway, and motor operated devices for swinging said frame about its axis and for driving said cutting mechanism including a motor mounted on and adjustable with said frame.
23. In a mining apparatus, a wheel supported body adapted to travel along a mine trackway, a frame mounted on said body for horizontal swinging movement relative thereto about a vertical axis, said frame overhanging the front end of said body, kerf cutting mechanism including a kerf cutter pivotally mounted on the outer extremity of said frame to swing horizontally relative thereto about an axis parallel to said frame axis, said kerf cutter being freely swingable relative to said frame, releasable devices for locking said kerf cutter in different predetermined angular positions about its pivot.

relative to said frame, said frame being adjustable in a vertical direction to vary the elevation of said kerf cutter, motor operated devices for adjusting said frame in aforesaid vertical direction to position said kerf cutter to cut a horizontal kerf at the level of the mine floor outside and below the level of the mine trackway, and motor operated devices for swinging said frame about its axis and for driving said cutting mechanism including a motor mounted on and adjustable with said frame.

24. In a mining apparatus, a wheel supported body adapted to travel along a mine trackway, a horizontal turntable mounted on said body for rotation relative thereto about a vertical axis, a frame mounted on said turntable and having an arm portion overhanging the front end of said body, kerf cutting mechanism including a kerf cutter pivotally mounted on the outer extremity of said arm portion to swing horizontally relative thereto about an axis parallel to the turntable axis, said turntable being adjustable in a vertical direction to vary the elevation of said kerf cutter, motor operated devices for adjusting said turntable in aforesaid vertical direction to position said kerf cutter to cut a horizontal kerf at the level of the mine floor outside and below the level of the mine trackway, and motor operated devices for swinging said frame about its axis and for driving said cutting mechanism including a motor mounted on and adjustable with said turntable.

25. In a mining apparatus, a wheel supported body adapted to travel along a mine trackway, a horizontal turntable mounted on said body for rotation relative thereto about a vertical axis, a frame mounted on said turntable and having an arm portion overhanging the front end of said body, kerf cutting mechanism including a kerf cutter pivotally mounted on the outer extremity of said arm portion to swing horizontally relative thereto about an axis parallel to the turntable axis, said kerf cutter being freely swingable about its axis relative to said arm portion, releasable devices for locking said kerf cutter in different predetermined angular positions about its pivot, said turntable being adjustable in a vertical direction to vary the elevation of said kerf cutter, motor operated devices for adjusting said turntable in aforesaid vertical direction to position said kerf cutter to cut a horizontal kerf at the level of the mine floor outside and below the level of the mine trackway, and motor operated devices for rotating said turntable relative to said body and for driving said cutting mechanism including a motor mounted on and adjustable with said turntable.

In testimony whereof I affix my signature.
MORRIS P. HOLMES.
